Boots Pure Drug Company Limited, Notting-
ham, England, a British company

No Drawing. Application June 6, 1935, Serial
No. 25,342. In Great Britain June 26, 1934

11 Claims. (Cl. 260—127)

This invention relates to the production of tetra-alkylated-diamines, and more particularly to the production of tetra-alkyldiamino derivatives of the paraffin series in which the number 5 of carbon atoms of the hydrocarbon chain is any number from 8 to 12 inclusive, and the alkyl groups of the dialkyldiamino radicles are each either butyl or amyl groups. The tetra-alkylated-diamines which come into question are therefore of 10 the general formula $(CH_2)_n(NR_1R_2)_2$, where n is any number from 8 to 12 inclusive and R_1 and R_2 is each a butyl or amyl group. Some of these diamines have very considerable amoebicidal properties of the same order of activity as emetine, 15 and are valuable, for example, in the treatment of dysentery and as emetine is relatively expensive and toxic, it is a desideratum to provide other substances having amoebicidal properties of the same order.

According to the present invention, the desired tetra-alkyldiamino derivative is formed by heating at a suitable temperature a dihalide, conveniently the dibromide of the corresponding hydrocarbon— $(CH_2)_nBr_2$ —with the appropriate secondary amine, NHR_1R_2 . It could not have been foreseen that the reaction could be made to proceed in this way to produce a considerable yield without the occurrence of secondary reactions to a substantial extent, nor could it have been foreseen that the derivatives when obtained would have any great therapeutic value as amoebicides.

The secondary amines required for use in the above reactions may be produced by hydrolysis of the corresponding para-toluenesulphonamides—
35 $CH_3C_6H_4SO_2NR_1R_2$ —which may be obtained by treating the sodium salt of para-toluenesulphonamide successively with alkyl bromides or other suitable derivatives such as alkyl chlorides or toluenesulphonates.

40 It will be understood that in carrying out the invention, the alkyl groups of the secondary bases may be varied, but in order that the invention may be clearly understood and readily carried into effect, some particular examples of methods of carrying out the invention will now be more fully described.

Example 1

In the preparation of $\alpha\kappa$ -tetra-n-amylaminon-decane, 8 parts of $\alpha\kappa$ -dibromodecane and 18 parts of di-n-amylamine are heated together under a condenser until a vigorous reaction commences. This is completed by heating the mixture on a steam bath for 24 hours, the reaction 55 going forward in the following way:

The product of the reaction is boiled gently with excess of caustic soda solution in order to decompose the hydrobromide which has been formed. The oil which separates, which consists of unchanged diamylamine and the required base, 5 is extracted with ether which is dried with sodium sulphate, and after removal of the ether, the bases are separated by distillation, the required base distilling over at 265° C. at a pressure of 20 mm. of mercury. The hydrochloride is a 10 neutral crystalline salt which melts at 72° C.

Example 2

In the preparation of sym $\alpha\kappa$ -di-n-amyl-n- 15 butyl-diamino-n-decane, 8 parts of $\alpha\kappa$ -dibromodecane and 16 parts of n-amyl-n-butylamine are heated together under a condenser until a vigorous reaction commences. This is completed by heating the mixture on the steam bath for 24 20 hours. The mixture of oil and crystals is allowed to cool, mixed with dry ether and filtered, amyl-butylamine hydrobromide remaining undissolved. The required base is isolated from the ether solution by distillation. It boils at 257–262° C. at a 25 pressure of 17 mm. of mercury.

The n-amyl-n-butylamine used in the above example has a boiling point of 178° C. and may be produced by hydrolysis of para-toluenesulphonbutylamylamide, in the following manner. 30 The sodium salt of para-toluenesulphonamide is heated in solution with butyl-toluenesulphonate to form para-toluenesulphonbutylamide, the sodium salt of which is then treated with amyl-bromide to form para-toluenesulphonbutylamyl- 35 amide, which may be hydrolyzed with 70 per cent sulphuric acid in the usual manner.

Example 3

In the preparation of $\alpha\kappa$ -tetra-n-butyldiamino-n-decane, 15 parts of $\alpha\kappa$ -dibromodecane and 26 parts of di-n-butylamine are heated together for 72 hours on the steam bath and the reaction 45 mixture worked up as described in Example 3. The required base distills at 267° C. at a pressure of 30 mm. of mercury. The neutral tartrate of this base is a crystalline solid having a melting point of 87° C.

Example 4

In the preparation of $\alpha\kappa$ -tetra-n-amylaminon-decane, 1 part of $\alpha\kappa$ -dichlorodecane and 3 parts of di-n-amylamine are heated together 55 for 12 hours under reflux and the product worked up by either method described in the other examples.

The boiling points of some other members of the series of tetra-alkylated-diamines produced 60

in accordance with the present invention have been determined and are as follows:—

	Pressure (mm.)	Boiling point
5 $\alpha\kappa$ -tetra-iso-amylidamino-n-decane	6	235° C.
10 $\alpha\kappa$ -tetra-n-amylidamino-n-undecane	18	272-275° C.
15 $\alpha\kappa$ -tetra-n-butylidamino-n-dodecane	11	245° C.

We claim:—

1. The process for the production of a tetra-alkyldiamino derivative of the paraffin series, which consists in reacting a dihalide of a hydrocarbon of the paraffin series containing a number of carbon atoms from 8 to 12 inclusive with a dialkylamine in which each of the two alkyl radicles is one of the group consisting of butyl and amyl. 15
2. The process for the production of a tetra-alkyldiamino derivative of the paraffin series, which consists in the steps of heating a dihalide of a hydrocarbon of the paraffin series containing a number of carbon atoms from 8 to 12 inclusive with a dialkylamine in which each of the two alkyl radicles is one of the group consisting of butyl and amyl until completion of the reaction, separating the desired derivative from the 20 reaction mixture, and purifying said derivative by distillation. 25
3. The process for the production of a tetra-alkyldiamino derivative of the paraffin series, which consists in the steps of heating a dibromide of a hydrocarbon of the paraffin series containing a number of carbon atoms from 8 to 12 inclusive with a dialkylamine in which each of the two alkyl radicles is one of the group consisting of butyl and amyl until completion of the reaction, decomposing the alkylamine hydrobromide 30 formed, and purifying the desired derivative by distillation. 35
4. The process for the production of a tetra-alkyldiamino derivative of the paraffin series, which consists in the steps of heating a dibromide 40

of a hydrocarbon of the paraffin series containing a number of carbon atoms from 8 to 12 inclusive with a dialkylamine in which each of the two alkyl radicles is one of the group consisting of butyl and amyl until completion of the reaction, removing dialkylamine hydrobromide by 5 filtration, and purifying the desired derivative by distillation. 10

5. The process for the production of $\alpha\kappa$ -tetra-n-amylidamino-n-decane, which comprises heating $\alpha\kappa$ -dibromodecane with about four molecular proportions of di-n-amylamine until completion of the reaction, separating the desired derivative from the reaction mixture, and purifying said derivative by distillation. 15

6. The process for the production of sym $\alpha\kappa$ -di-n-amylid-n-butylidamino-n-decane, which comprises heating $\alpha\kappa$ -dibromodecane with about four molecular proportions of n-butyl-n-amylamine until completion of the reaction, separating the desired derivative from the reaction mixture, and purifying said derivative by distillation. 20

7. The process for the production of $\alpha\kappa$ -tetra-n-butylidamino-n-decane, which comprises heating $\alpha\kappa$ -dibromodecane with about four molecular proportions of di-n-butylamine until completion of the reaction, separating the desired derivative from the reaction mixture, and purifying said derivative by distillation. 25

8. A tetra-alkyldiamino derivative of the paraffin series containing a number of carbon atoms from 8 to 12 inclusive in the hydrocarbon chain and in which each of the alkyl radicles of the dialkylamine group belongs to the group consisting of butyl and amyl, said derivative having a 30 high amoebicidal efficiency. 35

9. The amoebicidal product $\alpha\kappa$ -tetra-n-amylidamino-n-decane.

10. The amoebicidal product sym $\alpha\kappa$ -di-n-amylid-n-butylidamino-n-decane. 40

11. The amoebicidal product $\alpha\kappa$ -tetra-n-butylidamino-n-decane.
